UNITED STATES PATENT OFFICE.

WILLIAM H. GRAHAM, OF CUERO, TEXAS.

DESIGN FOR A WATCH-CHAIN.

SPECIFICATION forming part of Design No. 16,081, dated May 12, 1885.

Application filed February 16, 1885. Term of patent 14 years.

To all whom it may concern:

Be it known that I, WILLIAM H. GRAHAM, of Cuero, in the county of De Witt and State of Texas, have invented and produced a new and original Design for a Rosary Watch-Chain, of which the following is a full, clear, and exact description.

The object of my invention is to provide a new and original design for a rosary watch-chain.

Reference is to be had to the accompanying drawing, forming part of this specification, in which my new design for the rosary watch-chain is shown.

15 The double-strand chain A, of any well-known pattern, is provided with the beads or balls B and the hearts C.

D is the hook for fastening the chain on the watch-case bow.

20 E is an image of the "Virgin Mary" on one end of the chain.

F is a heart at the other end of the chain; G, a chain pendent from the heart F.

H is a watch-key in the shape of a crucifix on the end of the chain G.

25 J is a suspending-chain on the heart F, and K a bar on the end of the chain J.

I claim—

1. The herein-described new design for a watch-chain, consisting of the chain A, having the beads B and hearts C, the image, E, of the Virgin Mary, the hook D, the heart F, the chain J, the chain G, having beads B and hearts C, and the cross-bar K and the cross watch-key H, substantially as set forth. 30

2. The herein-described new design for a watch-chain, consisting of the chain A, having beads B and hearts C, the image, E, of the Virgin Mary, the hook D, the heart F, the chain J, the bar K, the chain G, and the cross 35 watch-key H, substantially as set forth. 40

WILLIAM H. GRAHAM.
